[57] CLAIM

The ornamental design for a golf club head, as shown and described.

DESCRIPTION

FIG. 1 is a perspective view showing the golf club head of my invention;

FIG. 2 is a left side view showing the golf club head of my invention, the right side view being the mirror image thereof;

FIG. 3 is a rear view thereof;

FIG. 4 is a top view thereof;

FIG. 5 is a bottom view thereof; and,

FIG. 6 is a front view looking at the face of the golf club head of my design.

The broken line showing of a fragmented shaft is for illustrative purposes only and forms no part of the claimed design.
